[57] CLAIM

The ornamental design for a clamp for automobile window repair, as shown.

DESCRIPTION

FIG. 1 is a side elevational view of a clamp for automobile window repair showing my new design, the opposite side being a mirror image thereof;

FIG. 2 is a left side elevational view thereof;

FIG. 3 is a right side elevational view thereof;

FIG. 4 is a top plan view thereof; and

FIG. 5 is a bottom view thereof.

FIG. 4

FIG. 5
